UNITED STATES PATENT OFFICE.

KARL HERMAN, OF TRENTON, NEW JERSEY.

AIR NOZZLE FOR DRYING PURPOSES.

Application filed December 7, 1925. Serial No. 73,825.

This invention relates to air nozzles for drying purposes and its objects are to provide a nozzle with which moistened articles may be quickly dried.

5 These objects, and other advantageous ends which will be described hereinafter, I attain in the following manner, reference being had to the accompanying drawings in which

10 Figure 1 is a plan view of a nozzle made in accordance with my invention,

Figure 2 a section on line 2—2 of Figure 1,

15 Figure 3 a side view of the nozzle shown in Figure 1,

Figure 4 an enlarged fragmentary section through the wall of the nozzle and a moistened article illustrating the drying action thereon, and

20 Figure 5 a modified form of nozzle.

Referring to the drawings, and more particularly to Figures 1-4, 1 indicates a cup-shaped chamber, 2 an inlet leading to the bottom of the chamber and 3 perforations 25 in the inner wall 4 of the chamber. The nozzle is preferably cast in one piece, but if desired may be readily made from stamped metal. The inlet 2 is suitably connected with a hose or pipe of an air line for receiving air therefrom.

30 In Figure 5, I have shown the chamber 1^a provided with an angular inlet 2^a and a convex wall 4^a having the perforations 3^a therein. The function of this nozzle is similar 35 to the one shown in Figures 1 to 4 except that it is better adapted for drying articles of different shape.

Assuming the nozzle to be connected with 40 an air line, the air turned on, and an article 5, indicated in dot-and-dash lines at 6 in Figure 2 is to be dried, the nozzle shown in Figures 1-4 is placed over the article as shown in Figure 2, so that the air coming into the chamber through inlet 2 at a certain 45 velocity, will leave the chamber through perforations 3 at a higher velocity and will impinge against the surface of the article, and thus dry the same. The drying action is due to the air (see Figure 4), escaping

through each perforation and impinging 50 against the surface of article 5, being deflected radially in all directions along the surface of the article to a point 7 where it meets similar currents of air from the adjacent perforations, and thus causes the 55 strata of air immediately surrounding the article to move at a high velocity in all directions. This lowers the pressure of the air immediately surrounding the article and thereby hastens evaporation of the moisture 60 on the article.

While I have described my invention as taking a particular form, it will be understood that the various parts may be changed without departing from the spirit thereof, 65 and hence I do not limit myself to the precise construction set forth, but consider that I am liberty to make such changes and alterations as fairly come within the scope of the appended claims.

Having thus described my invention, what I claim as new and desire to secure by Letters Patent is:—

1. An air nozzle for drying moistened articles comprising an air casing provided 75 with an annular extension and an inlet pipe, the inner wall of said extension being perforated to effect a discharge of air from said casing into the space surrounded by said extension at a higher velocity than the velocity of air entering said inlet.

2. An air nozzle for drying moistened articles comprising an air casing provided with an imperforate wall and a perforated wall 80 relatively spaced with respect to each other, said imperforate wall having an air inlet opening therein, said casing having an annular portion extending above the plane of the perforated wall, the inner wall of said extension being perforated, the perforations 85 in said walls being of a size to effect discharge of air from the casing into the space surrounded by said annular portion at a higher velocity than the velocity of air passing through said inlet.

90 In testimony whereof I have signed my name to this specification.

KARL HERMAN.
